DESIGN FOR A PLANTING BAR

John M. Council, Wananish, N. C.

Application September 17, 1935, Serial No. 58,600

Term of patent 14 years

To all whom it may concern:

Be it known that I, John M. Council, a citizen of the United States and a resident of Wananish, in the county of Columbus and State of North Carolina, have invented a new, original, and ornamental Design for Planting Bars, of which the following is a specification:—

Reference is had to the accompanying drawing, forming part thereof;

I claim:

The ornamental design for a planting bar, as shown.

JOHN M. COUNCIL,
